JOSEPH A. KEYES Inventor

By HIS Attorney O. V. Thiele

UNITED STATES PATENT OFFICE.

JOSEPH A. KEYES, OF NEW YORK, N. Y., ASSIGNOR TO LOCOMOTIVE SUPERHEATER COMPANY, OF NEW YORK, N. Y., A CORPORATION OF DELAWARE.

DAMPER.

1,349,068.

Specification of Letters Patent. Patented Aug. 10, 1920.

Application filed February 12, 1918. Serial No. 216,787.

To all whom it may concern:

Be it known that I, JOSEPH A. KEYES, a citizen of the United States, residing in the city of New York, State of New York, have 5 invented certain new and useful Improvements in Dampers, of which the following is a specification.

My invention relates to dampers used on locomotives equipped with smoke tube super- 10 heaters, and particularly locomotives of this kind used in switch or yard service. The object of my invention is to provide an im- proved mechanism for automatically causing the damper to assume the desired position 15 in response to certain varying conditions.

Those familiar with this art know that the damper arrangement in the case of road engines, that is locomotives whose service conditions are such that the periods during 20 which the throttle is open are long compared with those during which it is closed, is different from the arrangement in switch engines, where the periods of closed throttle are more frequent and longer. In the former 25 the arrangement is such that the damper which controls the flow of the hot gases through the flues containing the superheater units is open at all times when the throttle is open and the pressure in the steam chest 30 is above a certain predetermined point, and closed at all other times. For certain well-understood reasons this arrangement would be undesirable on switch engines and a different arrangement has been proposed, *i. e.* to 35 have the damper act in response to the pressure conditions in the pipe leading to the blower, the damper being open and allowing hot gases to flow over the superheater pipes at all times except when the blower is on, ir- 40 respective of whether the throttle is open or closed. This, in turn, resulted in the disadvantage that if the blower happened to be on while the throttle was open, no hot gases passed through the flues, resulting in a de- 45 creased steam production and a lack of superheat. Arrangements for remedying this have been worked out, involving the principle of two opposing pistons, one acted on by steam from the steam chest or steam 50 pipe and the other by blower steam. While these arrangements are entirely practicable, they are open to some objections, *e. g.* the objection that an entirely different damper cylinder arrangement is required in the two 55 classes of locomotives. One purpose of my

invention is to remove this objection, making it possible to use the same standard damper cylinder in all cases. Other objects will be apparent from the following description.

My invention is illustrated in the accom- 60 panying drawing, in which Figure 1 repre- sents the front end of a locomotive with my device in place; and Fig. 2 represents to an enlarged scale a central longitudinal section of the essential part of my device. 65

The barrel of the locomotive is designated by the reference numeral 1. The front tube sheet 2 has secured in it the flues 3 and the fire tubes 3^a. From compartment 4 of header 5 lead the superheater units 6, their other 70 ends, not visible as they lie behind those shown in the drawing, opening into compartment 7 of the header 5. It is understood that there is any desired number of tiers of these flues and superheater units. 75 8 is the inlet for the saturated steam, which is delivered to it from the boiler by the dry-pipe 8^a and 9 the outlet for the steam after it is superheated. The fixed plate 10 together with the rotatable damper 11 controls 80 the exit for the hot gases from the flues 3. As far as described the arrangement is typi- 85 cal and well-known.

The damper 11 is mounted on and rotates with the shaft 12. Keyed or otherwise se- 90 cured to this shaft is the arm 13 carrying at its end the weight 14. The relative position of arm 13 and damper 11 on shaft 12 is such that with the weight in its upper position, as in the drawing, the damper is closed, the 95 damper in this position being indicated in full lines as far as it shows in the view, the lower position of the weight and the open position of the damper being indicated by line 13¹ and 11¹ respectively. 95

Also secured to shaft 12 is the arm 15, whose end is connected to the end of arm 16 by link 17. Arm 16 is keyed to shaft 18 to which is also keyed arm 19. The other end of arm 19 extends into a slot in piston rod 20. 100 At the lower end of 20 is the piston 21, re- ciprocable in cylinder 22. To the lower end of 22 is secured the valve casing 23. This casing, illustrated on a larger scale in longi- 105 tudinal section in Fig. 2, is generally cylind- 110 rical, and has a longitudinal cylindrical hollow space, 23^a, which is of one diameter for a portion of its length and of a different diameter for the remainder. Slidably fitted into this chamber is the piston valve 24,

which has a larger piston, 25, and a smaller one, 26, movable respectively in the larger and smaller portions of the chamber. They are connected by a rod, preferably integral with them, which has two portions differing in diameter, the one 28 adjacent to the piston 25 making a sliding fit in the smaller portion of the hollow interior of the casing, and the smaller portion 27, adjacent to the piston 26, leaving an annular space between it and the chamber wall.

The two pistons are preferably grooved to prevent leakage.

The casing is screwed into the bottom of the cylinder 22 by means of the connection 29, and its interior communicates with the space below piston 21 by means of the passage 30, opening into the smaller diametered portion of the chamber 23^a. From the end 20 of the same portion of the chamber connection is made, by means of passage 31 and pipe 32, with the blower pipe 33.

The end of the larger portion of chamber 23^a communicates by means of passage 34 25 and pipe 35 with the steam chest 36.

Leading from the smaller portion of chamber 23^a to the air is a passage 37. Screwed into it and leading to any convenient point of discharge is pipe 38. Connecting this passage 37 with the near end 50 of the larger portion of the chamber is the small passage 39.

The disposition of the inner ends of passages 30 and 37 is such that when the piston valve is at the left, in the position shown in the figure, both passages are open but communication between them is closed by piston 26; but when the valve is in the opposite position, *i. e.* in its extreme right 40 position, the two passages communicate through the annular space around portion 27 of the stem and at such times communication is interrupted between 30 and 31.

It will be noted that as piston 25 approaches the left end of its travel steam in the larger end of the chamber 23^a can escape only through the comparatively small passage 34, and as it approaches the right end of its stroke, steam trapped in the inner end of the large portion of the chamber 23^a can escape only through the small passage 39. In this way the stroke of the valve is properly cushioned.

The operation of the device is as follows: 55 When the locomotive is standing still with the throttle closed and the blower on, pressure from the blower pipe 33, passing through pipe 32 and passage 31, will move piston valve 24 to the left, there being no pressure opposing this movement. Steam can then pass by way of passage 30 to damper cylinder 22. This will force piston 60 21 into its upper position, closing damper 11 in opposition to the action of weight 14. 65 If now the main throttle is opened, steam

from the steam chest 36, coming through pipe 35 and passage 34, exerts pressure on the outer side of piston 25. The area subject to this pressure being greater than the area of piston 26, the piston valve will move 70 toward the right. Port 30 will then be in communication with port 37 but no longer with 31, and the steam in cylinder 22 escapes. The weight 14 then puts the damper into its open position. Any steam that leaks 75 by piston 25 is free to escape by way of passage 39. Should the blower be turned off at times when the throttle is open, the action will be, of course, as just described. Should it be turned off at a time when the throttle 80 is closed, the position of piston valve 24 would make no difference, as no steam pressure would oppose the action of weight 14 which would therefore be free to open the damper. 85

What I claim is:—

1. In apparatus of the class described, the combination of a boiler having flues, a superheater with a portion of its heating surface located in the flues, a compartment into which the flues discharge gases, a damper controlled opening in the wall of said compartment, a steam chest, a blower pipe, means to operate the damper comprising a cylinder, and a valve subject to opposing pressures from the steam chest and the blower pipe respectively controlling the admission of steam to and its exhaust from said cylinder.

2. In apparatus of the class described, the combination of a boiler having flues, a superheater with a portion of its heating surface located in the flues, a compartment into which the flues discharge gases, a damper controlled opening in the wall of said compartment, a steam chest, a blower pipe, steam actuated means connected with the damper and tending to close it when supplied with steam, a valve to admit steam to said means, said valve operating in response to pressure in the blower pipe to admit steam to the means, and in response to pressure from the steam chest to cut it off. 110

3. In apparatus of the class described, the combination of a boiler having flues, a superheater with a portion of its heating surface located in the flues, a compartment into which the flues discharge gases, a damper controlled opening in the wall of said compartment, a steam chest, a blower 115 pipe, steam-operated means operatively connected with the damper and tending to close it when supplied with steam, and other means to supply steam to said steam-operated means when the blower pipe is receiving steam and the steam chest is not, and to cut off the steam supply when the steam chest is receiving steam. 120

4. In apparatus of the class described, the combination of a boiler having flues, a 130

superheater with a portion of its heating surface located in the flues, a compartment into which the flues discharge gases, a damper controlled opening in the wall of 5 said compartment, a steam chest, a blower pipe, a damper cylinder, a piston reciprocable in it and operatively connected with the damper and tending to close it when there 10 is pressure in the cylinder, and a differential piston valve the larger of whose two piston areas is subject to pressure from the steam

chest the smaller being subject to blower pipe pressure, the piston valve admitting steam to the damper cylinder when in the position it tends to assume in response to 15 the blower pipe pressure, and connecting it with the atmosphere when in the position it tends to assume in response to the steam chest pressure, and automatic means to open the damper when there is no pressure in 20 the damper cylinder.

JOSEPH A. KEYES.
